UNITED STATES PATENT OFFICE.

WILLIAM J. BAKER, OF NEWPORT, KENTUCKY.

WINDOW-SCREEN.

No. 890,398.

Specification of Letters Patent.

Patented June 9, 1908.

Application filed October 3, 1907. Serial No. 395,722.

To all whom it may concern:

Be it known that I, WILLIAM J. BAKER, residing at Newport, in the county of Campbell and State of Kentucky, have invented 5 certain new and useful Improvements in Window-Screens, of which the following is a specification.

My invention relates to certain new and useful improvements in window screen construction, and in its general nature the invention embodies a sheet metal frame window screen composed of a frame formed of one or two parts in such manner as to hold the wire screen securely locked to the frame, 15 without the necessity of using screws, rivets or bolts.

Specifically my invention embodies an improved construction of frame having interlocking parts for the screen clamping portion, so arranged that the screen can be readily removed from the frame for replacement when worn.

In its more subordinate nature, the invention embodies certain novel features of construction, and detailed arrangement of parts, all of which will be first described, then be specifically pointed out in the appended claims, and illustrated in the accompanying drawings, in which:—

Figure 1 is a front elevation of a screen embodying one form of my invention, showing how the same may be secured in the window frame. Fig. 2, is a horizontal section on the line 2—2 of Fig. 1. Figs. 3 to 16 inclusive 35 are detail views of various modifications hereinafter specifically referred to.

Referring now to the accompanying drawings, in which like letters and numerals of reference indicate like parts in all of the figures, it will be seen that the screen A comprises a sheet metal frame consisting of the top frame section *a* and the bottom frame section *b*, both of which may be of the same cross sectional type, or form, while the side 45 sections *c* may be of the same sectional form as the top and bottom sections *a* and *b*, or they may have a different sectional form and provided with integral guides, when it is desired to use the metal screen in a window frame having wooden slide bars *B* in place of metal slides.

C designates fixed slide engaging members carried by one side section *c* to engage the slide bars *B* while the other side section *c* car-

ries sliding lock members *D* to engage the slide bars *B*, the sliding lock members *D* being capable of withdrawal from engagement with the slide bars *D* to permit of the removal of the screen. The screen also includes a wire screen section *W* which is held 60 by the sheet metal frame sections *a*, *b* and *c*.

The frame sections, *a*, *b* and *c* may be of various forms in cross section and I have illustrated numerous modifications of my improved form of screen in the accompanying drawings, by reference to which it will be seen that in the form shown in Fig. 3, the screen frame section consists of a flat bottom or base 1 with upwardly extending integrally formed sides 2 and 3 arranged parallel 70 to one another and spaced apart, the upper ends of which are bent as at 2^a and 3^a, one of said ends 2^a overlapping the other 3^a, as shown. Each of the overlapping ends 2^a, 3^a have their edges bent back upon themselves as at 3^b and 2^b respectively, the edges 2^b and 3^b being bent to lie between the ends 2^a and 3^a respectively, as clearly shown in the drawings.

The screen wire *W* is clamped between the 80 ends 2^a and 3^a and the edges 3^b and 2^b and the side wall 2 of the frame section, as clearly shown in the drawings, giving the screen wire, as it were, an S-shaped bend where it passes between the ends 2^a and 3^a of the 85 sheet metal frame section. It will also be seen that by this construction the edges 2^b—3^b lie substantially in the same plane when the screen is clamped in the frame and thus prevent the screen drawing out, and furthermore keep the sides 2 and 3 in parallel 90 relation.

Instead of making the screen sections in one piece, as shown in Fig. 3, the same effect can be obtained by constructing the sections 95 as shown in Fig. 4, wherein the screen section is formed of two parts, the base 1 being formed partly on one part and partly on the other, and consists of the portion 1^a, bent at right angles to the side 2 and toward the 100 other side 3 and given a slightly curved form to coöperate with the base portion 1^b that is formed with the side 3 and extends toward the side 2, the edge of the base portion 1^b being bent under, as at 1^c, to coöperate with the 105 base portion 1^a and form, as it were, a rigid structure.

In Fig. 5, I have shown a further modifica-

tion of my invention, and in this form the screen section is made in two pieces, as in the form shown in Fig. 4, but the base 1 in this form consists of flat base portions 1^a bent over at right angles from the side 2 and the flat base portion 1^b bent over at right angles from the side 3, the edges of which are bent over as at 1^c and 1^d, in a manner similar to the edges 3^b—2^b of the screen clamping portion of the frame, and when this form is used, it will be seen, when the two parts are placed together they will, owing to the resiliency of the metal, "spring lock" themselves in place and by reason of the folded or bent over edges 1^a—1^c and 3^b—2^b, the two parts will be prevented from coming apart.

Fig. 6, shows the same general idea disclosed in Fig. 5, with the exception that in this form of my invention the bent over edge 1^d is omitted, and in order to have its function duly performed, the bottom 1^a is bent upwardly to form a bead 1^e which corresponds to the end 1^d of Fig. 5.

In Fig. 7, I have shown the same form of screen shown in Fig. 6, but adapted for use as the side screen section *e*, of the screen, and in this form an integral guide 1^f is projected downwardly from the member 1^e and this guide may have its end 1^g bent back to form a stiffening portion, as may be found desirable.

Fig. 8 shows essentially the same idea disclosed in Fig. 7, with the exception that in this form the bent over edge 1^c is omitted and its function is performed by providing the bottom 1^b with a bead 1^h to bring the bottom 1^b into two different planes, one portion 1^v of the bottom 1^b being in a lower plane than the other portion thereof and performing the function of the bent over edge 1^c, as clearly shown in the drawings.

In Fig. 9, I have shown another modification of my invention.

In Fig. 10, I have shown another modification of "bottom" construction, in which the bottom 1^a is formed one-half integral with one side 2 and the other half integral, with the part 3, the two bottom portions 1^a—1^b overlapping, as before, but each of these bottom portions 1^a—1^b are provided with a longitudinal corrugation or bead 1^r and 1^s which are adapted to register with one another and thus lock the two bottom portions 1^a—1^b together into a rigid structure.

Fig. 11 illustrates the same form shown in Fig. 10, with an integrally formed guide 1^f formed with the bottom portion 1^a.

Fig. 12 illustrates a further modification of the clamping surfaces of the frame section. In this form the upper ends of the sides 2 & 3 are bent inwardly toward one another to lie in parallel planes, as at 3^a—2^a in a manner similar to that shown in Fig. 3 of the drawings and in this form where the side 3 and ends 3^a meet an inwardly depressed

corrugation 3^x is provided to coöperate with a bead 2^x correspondingly formed on the edge of the end 2^a.

Fig. 13 shows another modification of the general type disclosed in Fig. 3, of the drawings, but in this form the bent over edge 3^b is omitted and in lieu thereof its function is performed by bending up the edge 3^y of the end 3^a of the side 3 thereof so as to form a channel for the screen of substantially an S-shape 75 similarly to the manner disclosed in Fig. 3, but in this form the base 1 is formed integral with the sides 2 and 3.

Fig. 14 illustrates the same form shown in Fig. 13 with the base 1 formed of two members, one of which 1^a, is formed with the side 2 and the other 1^b is formed with the side 3, the two members over-lapping and interlocking, as shown.

Fig. 15 shows another modification of my invention which is substantially the same as Fig. 12, except that both the top and bottom portions of the screen sections are formed alike and in this form also the fixed guide 1^f may be provided, or omitted, as the case 90 may be.

From the foregoing, it will be seen that in each form of my invention the screen frame section comprises a base 1, parallel sides 2 and 3 and a top 5, formed by bending over the upper ends of the sides 2 and 3, as hereinbefore described, and in some cases the bottom is made by bending over the lower ends of the sides 2 and 3 as at 1^a—1^b, thus forming what is known in the art as a two-piece 10 screen. When I refer to the upper ends of the sides 2 and 3 of the screen section I intend that term to be read in connection with the parts in the position shown in Sheet 2 of the drawings containing Figs. 3 to 16, inclusive, and to include within its definition the parts 2^a—3^a of the sides 2 and 3, and the equivalents of such parts 2^a and 2^b, the expression "upper ends" being a relative term used in order to clearly define the features of 11 applicant's invention.

From the foregoing description taken in connection with the accompanying drawings, it is thought the complete construction, operation and many advantages of my invention will be readily understood by those skilled in the art to which the invention appertains, and in order to release the screen cloth from the frame, it is only necessary to insert a screw driver, or other similar tool, 12 between the ends 3^a and 2^a, and pry the same apart, thus permitting the sides 2 and 3 to be pried apart out of parallelism, or when the form of the general type shown in Fig. 5 is used, by prying apart the ends 3^a and 2^a, 13 which form the top the part having the side 3 may be entirely removed.

Any suitable corner braces may be provided for the screen, such for instance, as shown in Fig. 16, of the drawings, by refer-

ence to which it will be seen that a reinforcing strip may be provided at the corners, and by reason of the bent over edges of the frame section no rivets are required to secure the parts together.

5 What I claim is:

1. In a window screen, a sheet metal frame section, comprising a base and parallel side portions, the upper ends of which are bent 10 at right angles to the side portions, the bent over end of one side portion projecting toward that of the other side portion, one of said ends overlapping the other, said ends being provided with portions lying in the 15 same plane and other portions lying in different parallel planes, and a wire screen member clamped by said frame section, substantially as shown and described.

2. In a window screen, a sheet metal frame section, comprising a base and parallel side portions, the upper ends of which are bent at 20 right angles to the side portions, the bent over end of one side portion projecting toward that of the other side portion, one of 25 said ends over-lapping the other, said ends being provided with portions lying in the same plane and other portions lying in different parallel planes, and the bottom being formed of a plurality of parts, one of said 30 parts formed integrally with one side portion and the other part formed integrally with the other side portion, and a wire screen member clamped by said frame section, substantially as shown and described.

3. In a window screen, a sheet metal frame section formed of two parts, each having a base portion and a side portion and a top portion bent over at right angles to the side portion, one of said parts adapted to fit into the 40 other part with the base portions of each part superimposed and the top portions of each part over-lapping one another, said top portions each having its edge bent over to lie in a plane between the over-lapping top 45 portions of the respective sheet metal parts and a wire screen member clamped by the two parts of the frame section, substantially as shown and described.

4. A window screen composed of sheet 50 metal sections said sections each being formed in two parts each of said parts having a side and top, and bottom portions bent at substantially right angles to said sides, one of said parts fitting within the other, each

of said parts having the edge of their top and 55 bottom portions bent over whereby when the parts are fitted together the bent over edges of the bottom portion of each part will lie in a different plane than the remainder of said bottom portions, and a wire screen 60 member clamped by said parts, substantially as shown and described.

5. A window screen composed of sections each consisting of a plurality of sheet metal parts, each of said parts having a side and 65 top, and bottom portions bent at substantially right angles to said sides, one of said parts fitting within the other, each of said parts having the edge of their top and bottom portions bent over whereby when the 70 parts are fitted together the bent over edges of the bottom portion of each part will lie in a different plane than the remainder of said bottom portions, the bent over edges of the top portions will lie in a plane between 75 those containing the remainder of the top portions of the parts, and a wire screen member clamped by said parts, substantially as shown and described.

6. In a window screen, sheet metal sections each consisting of two sheet metal parts, one of said sheet metal parts having a side and top and bottom portions bent over at substantially right angles to said sides, one of 80 said parts having its bottom terminating in a downwardly projecting guide member, each of said parts having the edge of their top portions bent over to lie in a plane parallel with the remainder of the top portions, substantially as shown and described. 90

7. A window screen comprising sheet metal sections each consisting of two sheet metal parts, one of said sheet metal parts having a side and top and bottom portions bent over at substantially right angles to said sides, 95 one of said parts having its bottom terminating in a downwardly projecting guide member, each of said parts having the edge of their top portions bent over to lie in a plane parallel with the remainder of the top portion, and in a plane intermediate that containing the remainder of the top portions of the respective section parts substantially as shown and described. 100
